BUFFING MATERIAL PACKAGE

Robert S. Leather, Waterbury, Conn., assignor to
 The Lea Manufacturing Company, Waterbury,
 Conn., a corporation

Application January 9, 1934, Serial No. 705,885

3 Claims. (Cl. 206—56)

This invention relates to an improvement in buffering material packages, and particularly to a glue, water and abrasive compound which is applied to the surface of a buffering wheel, such as 5 loose cotton buff, bristle circular brush, wire circular brush, etc., to produce an abrading surface. This abrasive material in solid bar form is sensitive to the drying action of the atmosphere, and it is desirable that the container be 10 waterproof.

The object of this invention is to provide a waterproof container with provision for removing portions of the said container as the contents are used, and the invention consists in the construction as hereinafter described and particularly recited in the claims.

In the accompanying drawing:

Fig. 1 is a side view of a container for buffering material in solid bar form, constructed in accordance with my invention;

Fig. 2 is a side view, partly in section, on a larger scale, showing the container filled but with the cap removed;

Fig. 3 is a perspective view, partly broken away, illustrating the cap to be applied to the open end of the container;

Fig. 4 is a sectional view of the open end of the container, showing the closure-cap applied thereto, Fig. 4 being on a larger scale than Fig. 2;

Fig. 5 is a side view showing the upper end of the container torn away to expose the contents.

In carrying out my invention, I employ a tubular casing 6 formed from very thin metal, similar to that commonly used in collapsible tubes. This casing is drawn up from a disk of metal, forming a comparatively thick conical top 7 with a closed center 8. The other end of the container is formed with an outwardly-extending flange 9.

After the container has been filled with buffering material, a cap 10 is placed over the open end, this cap being formed with an inset central portion adapted to enter the open end of the container, and with a lip 11 adapted to permanently interlock with the flange 9 and form an air-tight seal. This cap is formed from metal of a thickness to prevent the collapsing of the closed end of the tube, and by projecting into the tube, firmly

holds the end of the container in its round shape.

In use, the top 7 is cut away, which may be readily done with the point of a knife or other sharp device, exposing the tapered end of the contents of the container, and this exposed end is pressed against a buffering wheel so as to transfer the contents of the container to the wheel. As the contents of the container are worn away, the open end of the container is torn off, which may 10 be readily done with the fingers, so as to expose the material for application to a buffering wheel, and this tearing away is continued until the contents of the container are exhausted.

When not in use, the exposed end of the material may be readily covered with any suitable means, so as to prevent exposure to the atmosphere.

I claim:

1. A new article of manufacture comprising: 20 an air-tight metal container including a casing; and a bar of water-containing solid buffering material filling said casing; said casing consisting of an elongated, transversely and longitudinally continuously integral side-wall and a top-end 25 cap, said casing being preformed to its final shape and size independently of said bar of buffering material, said side-wall being composed of metal the nature of which is such that portions thereof can be successively readily torn away with the 30 fingers to expose an end of the bar of buffering material as the latter is consumed.

2. A new article of manufacture comprising: 35 an air-tight metal container including a casing; a bar of water-containing solid buffering material filling said casing; said casing consisting of a cylindrical, transversely and longitudinally continuously integral side-wall and a top-end cap, said casing being preformed to its final shape and size independently of said bar of 40 buffering material, said side-wall being composed of metal the nature of which is such that portions thereof can be successively readily torn away with the fingers to expose an end of the bar of buffering material as the latter is consumed; 45 and the other end of said casing being permanently closed by an annular metal bottom-end cap.

3. A new article of manufacture comprising: 50 an air-tight metal container including a casing;

a bar of water-containing solid buffing material filling said casing; said casing consisting of an elongated, transversely and longitudinally continuously integral side-wall and a top-end cap, 5 said casing being preformed to its final shape and size independently of said bar of buffing material, said side-wall being composed of metal the nature of which is such that portions thereof

can be successively readily torn away with the fingers to expose an end of the bar of buffing material as the latter is consumed; and the other end of said casing being permanently closed by a metal bottom-end cap; said top- and bottom-end caps being substantially thicker than said side-wall. 5

ROBERT S. LEATHER.
